(57) CLAIM

The ornamental design for a pet grooming station, as shown and described.

DESCRIPTION

FIG. 1 is a front perspective view of pet grooming station, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another top perspective view thereof, but shown with the broken line subject matter shown in an open position of use for clarity of illustration;

FIG. 10 is another top perspective view thereof, but shown with the door feature shown in an open position of use for clarity of illustration;

FIG. 11 is an enlarged detail view of area 11 in FIG. 1;

FIG. 12 is an enlarged detail view of area 12 in FIG. 2;

FIG. 13 is an enlarged detail view of area 13 in FIG. 2;

FIG. 14 is an enlarged detail view of area 14 in FIG. 4; and, FIG. 15 is an enlarged detail view of area 15 in FIG. 7.

The broken lines in the drawings illustrate the portions of the pet grooming station that form no part of the claimed design. The long dash-short dash broken lines in FIGS. 1, 2, 4, 7, 11, 12, 13, 14 and 15 show the boundaries of the enlargements shown in FIGS. 11, 12, 13, 14 and 15, and form no part of the claimed design.
